TIMER

Mitchell A. Hall, 445 Rossford Ave., Fort Thomas, Ky.
Filed June 11, 1959, Ser. No. 819,593
14 Claims. (Cl. 200—35)

This invention relates to a timer mechanism, and particularly to a mechanism adapted to close an electric circuit to an appliance or other device to be operated for a predetermined length of time.

An object of the invention is to provide a simple, highly efficient, substantially foolproof time control mechanism which may be associated with any type of conventional means for providing a setting which will initiate the beginning of a predetermined time cycle.

A further object of the invention is to provide a time-control mechanism having the hereinabove described characteristics which is adapted to be associated with the standard housings or control boxes of coin-actuated equipment, such as, by way of example, electric driers, washers and the like, whereby the timer mechanism, though entirely independent of, may nevertheless be initiated and controlled by, the conventional coin-actuated slide type mechanisms usually associated with such housings.

Another object of the invention is to provide a time control mechanism having adjustable means associated therewith for enabling the timer to provide a wide variety of different timing cycles, depending upon the uses to which the timer is to be put, thereby greatly enhancing the flexibility and commercial acceptance of the device.

A further object of the invention is to provide a coin-slide-actuated timer which is so constructed and arranged as to preclude malfunction which would result in more time being delivered by the device than was actually paid for. In other words, the device is substantially cheat-proof.

Still a further object of the invention is to provide a time control mechanism which is characterized by its extreme accuracy and which is adapted to be mounted in a typical housing in such a manner that it cannot be tampered with or cheated on in any way. In the preferred embodiment of the invention the subject time control mechanism is secured to and carried by a lock-actuated access door, thereby rendering the device readily accessible to authorized persons for permitting easy removal of the entire mechanism for inspection and/or adjustment of the basic time setting.

These and other objects are attained by the means described herein, and as disclosed in the accompanying drawings, in which:

FIG. 1 is a side elevation of a typical housing or box containing coin injection mechanism, coin accumulating compartment and the time control mechanism of the present invention.

FIG. 2 is a rear end view of the box of FIG. 1.

FIG. 3 is a top plan view of the box of FIG. 1.

FIG. 4 is an enlarged fragmentary view of the box as shown in FIG. 1, partially broken away to illustrate the time control mechanism housed therein.

FIG. 5 is a top sectional view taken on line 5—5 of FIG. 4.

FIG. 6 is a vertical sectional view taken on line 6—6 of FIG. 5.

FIG. 7 is a view similar to FIG. 6, illustrating the mechanism in its actuating position.

2

FIG. 8 is a vertical cross-sectional view taken on line 8—8 of FIG. 5, illustrating the time control mechanism in its Off position.

FIG. 9 is a fragmentary section similar to FIG. 8, illustrating the mechanism in its On position.

FIG. 10 is a side elevation of certain parts of the mechanism as seen in FIG. 4, illustrating the relative movement of said parts.

FIG. 11 is a sectional view similar to FIG. 6, illustrating one position of a modified form of the invention.

FIG. 12 is a sectional view similar to FIG. 11, illustrating the second position of the modified form of the invention.

The box, as illustrated in FIGS. 1, 2 and 3, is generally rectangular in configuration, comprises side walls 20 and 21, top and bottom walls 22 and 23, and front and rear end walls 24 and 25. Front end wall 24 carries a conventional coin injecting slide mechanism, indicated generally at 26. When a coin of proper denomination is inserted in the circular aperture 27, the slide may be fully actuated and the coin injected into the box where it is deposited in a coin accumulating compartment, accessible through door 28 in side wall 20. Door 28 is provided with a lock 30. The coin controlled slide mechanism may be of any appropriate conventional construction and is not disclosed or described in detail as it forms no part of the present invention beyond the provision of a leading edge or abutment 31 (FIGS. 6 and 7) on the coin injecting slide 26.

Each time a proper coin is inserted in aperture 27 and injected into the box, the leading edge or abutment 31, being either integral with or rigidly attached to slide 26, moves into contact with and rocks a lever 32 from the position illustrated in FIG. 6 to the position illustrated in FIG. 7.

A tension spring 33 is attached at one end to an ear 34 integral with lever 32, and at its other end to an upstanding arm 35 forming part of a stop member 36. Stop member 36 is rigidly fixed to a base plate 37 by means of a detent 38 and rivet 40 and provides a stop or limit for lever 32. The edge 41 of lever 32 is yieldably urged against stop member 36 by tension spring 33 (FIG. 6).

Base plate 37 is fixed, as by spot welds, to a door plate 42, removably mounted in the end wall 25, and provided with a lock unit indicated generally at 43. Lever 32 is rotatably journaled on a collar 44 (FIG. 8) formed integral with base plate 37, and positioned to place lever 32 in the line of travel of the leading edge or abutment 31 of coin injecting slide 26.

Lever 32 is held in place on collar 44 and against base plate 37 by means of a ring bracket 138 encircling collar 44 and being provided with an offset foot portion 39, rigidly attached to base plate 37 by means of an appropriate screw 139.

A pawl 45 (FIG. 6) is pivotally attached to lever 32, as at 46, and is adapted to engage the teeth of ratchet wheel 48. A tension spring 50 extends between an ear 51 of pawl arm 45 and an ear 52 extending radially outwardly from the journal ring 53 of lever 32. Spring 50 holds pawl 45 in engagement with ratchet wheel 48.

As illustrated in FIG. 7, when the lever 32 is rocked in a counter-clockwise direction, pawl 45 will be moved out of engagement with tooth 54 of ratchet wheel 48 and shifted downwardly against lug 56 preparatory to engagement with the succeeding tooth 55. Overtravel of pawl

45 is thus limited by means of the upstanding lug 56, struck from base plate 37. Tension spring 33 will return lever 32 to its initial, upstanding or starting position (FIG. 6), whereupon pawl 45 will engage ratchet tooth 55 during the return stroke and thereby advance the ratchet wheel in a clockwise direction by one tooth.

As best illustrated in FIGS. 8 and 9, ratchet wheel 48 is provided with a central aperture 57 adapted to be slid over the counter-turned neck 58 of a hub 60 and is keyed thereto by means of a lug 61 struck from the ratchet wheel and extending into a keyway 62 provided in hub 60. The hub and ratchet wheel assembly is rotatably journaled in the bore 63 provided in the collar 44 and is held in place by means of an enlarged beveled head portion providing a shoulder 64 overlying the base plate 37 at one end of collar 44. Ratchet wheel 48 is held against the other end of collar 44 by means of a spring washer 65 and a split ring 66 seated in an annular groove 67 in the counter-turned neck portion 58 of hub 60. Sufficient friction is thus provided by the spring washer to prevent the hub and ratchet wheel assembly from rotating with the pawl as it travels in a counter-clockwise direction over the ratchet teeth. The return travel, under the influence of spring 33, readily overcomes the friction to rotate the ratchet wheel and hub assembly in a clockwise direction as illustrated in FIGS. 6 and 7.

As best illustrated in FIGS. 8 and 9, the hub 60 is provided with a central screw threaded bore 68 to receive an externally threaded stud 70 provided with a head portion 71 at its outer end which carries a second ratchet wheel 72. Ratchet wheel 72 is rigidly fixed to the head 71 of threaded stud 70 by means of a collar portion 73 swaged over the beveled periphery of the central aperture 74 of ratchet wheel 72. Rotary movement of ratchet wheel 72 is restricted by a pair of spring metal pressure pads 75 and 76 exerting an axially opposed pressure on opposite faces of the ratchet wheel as best illustrated in FIG. 5. The leg 77 of one pressure pad 75 is rigidly attached as by screw 78 to an ear turned outwardly from base plate 37. The other pressure pad 76 is fixed to the leg 77 of pressure pad 75 by means of a tab 80 extending through a slot 81 in leg 77 and a rivet 82, FIGS. 4 and 5.

The externally screw threaded stud 70 is also provided with a central bore 83. The forward or inner end 84 of bore 83 is somewhat smaller in diameter and is threaded to carry a set screw 85 which is adapted to contact a switch actuating plate 86.

As best illustrated in FIG. 5, plate 86 is pivoted, as at 87, at one end in a bracket 88 secured to base plate 37 by means of a screw 90. The other end 91 of plate 86 is adapted to contact button 92 of a micro-switch 93 under pressure of set screw 85, as will be described later in the specification. Micro-switch 93 is firmly supported between brackets 88 and 94.

Ratchet wheel 72 is driven in a clockwise direction by means of a control member indicated generally at 95, which is the subject matter of a co-pending application, Serial No. 819,355, filed June 10, 1959, and will be described only insofar as is necessary to understand the operation of the present invention.

The control member 95 is driven in a counter-clockwise direction by means of a clock motor 96, and is composed of a body portion 97 and a plurality of radially disposed adjustable stops or abutment plates 98 (FIGS. 2 and 10). Each abutment plate 98 terminates in an outturned lip 100, and is axially adjustable to either a fully retracted or a fully advanced position. In their fully advanced position, lip 100 will contact the teeth 101 of ratchet wheel 72 and impart a relative movement to the wheel. When the abutment plates are fully retracted, they by-pass or clear the teeth of ratchet wheel 72. Therefore, if motor 96 is driving the control member 95 in a counter-clockwise direction at a rate of one revolution per hour, for example, and if all twelve abutment plates are fully advanced as in FIG. 10, an abutment plate 98 will contact a tooth 101 of

5

ratchet wheel 72 every five minutes. The abutment plates 98 and ratchet teeth 101 are spaced, as illustrated in FIG. 10, so that each abutment stop or element 100 will drive the ratchet wheel 72 in a clockwise direction by an amount indicated by the distance between radial lines A and B.

In FIG. 4, every third stop or abutment plate has been fully advanced and the remainder are fully retracted. A fifteen minute interval will therefore elapse between the contacting of each ratchet tooth. Various other time intervals of either regular or irregular duration may be provided for, simply by advancing or retracting various abutment plates 98.

In operation, a coin of the required denomination is inserted in the aperture 27 of the injecting slide 26 and advanced in the conventional manner until the coin is deposited in the coin accumulating compartment. The leading edge of the injecting slide provides abutment 31 which rocks arm 32 in a counterclockwise direction. Pawl 45, pivotally carried by arm 32, rides out of engagement with tooth 54 of ratchet wheel 48 and into position to engage the succeeding tooth 55. When coin injecting slide is released, tension spring 33 returns lever 32 and pawl 45 to its starting position. The pawl, meanwhile, has engaged tooth 55 and rotated the periphery of ratchet wheel 48 a distance of equivalent to the length of one tooth. If the coin injecting slide is released suddenly, there may be an inclination for the pawl and ratchet wheel to bounce and possibly skip a tooth, due to the sudden stop against stop member 36. A tapered lock plate 102 is provided to eliminate this possibility. The tapered edge 103 lies in the plane of travel of pawl 45, and is positioned to be very closely adjacent to or to abut the top edge 104 of the pawl as edge 41 of lever 32 contacts stop 36. Pawl 45 is therefore held or locked in engagement with ratchet wheel 48. The tapered lock plate is fixed by a screw 105 to base plate 37.

The clockwise movement of ratchet wheel 48 is directly transmitted to hub 60 by means of lug 61 in keyway 62. Due to the friction created on sprocket wheel 72 by the pressure pads 75 and 76, ratchet wheel 72 will not rotate with ratchet wheel 48. Instead, the internally threaded bore of hub 60 threads or moves the stud 70 axially outwardly, carrying ratchet wheel 72 away from ratchet wheel 48. Set screw 85 is therefore withdrawn from contact with switch plate 86, permitting microswitch 93 to assume its normally On position.

Motor 96 is energized by switch 93 causing control member 95 to rotate in a counterclockwise direction. As previously described, each stop or abutment plate 98 moves the periphery of ratchet wheel 72 a distance exactly equal to the length of one tooth. The friction created by spring washer 65 on ratchet wheel 48 prevents relative rotation of ratchet wheel 48. Instead, stud 70 is threaded axially, inwardly, in hub 60, moving ratchet wheel 72 toward ratchet wheel 48. The amount of outward axial movement caused by the rotation of ratchet wheel 48 is exactly compensated for by the inward axial movement caused by the rotation of ratchet wheel 72. Therefore, the forward end of set screw 85 re-engages switch plate 86, imparting sufficient pressure to depress switch button 92 to disengage the contacts of microswitch 93.

In practice, the micro-switch, in addition to operating motor 96, may also be in electrical connection with a piece of machinery, appliance, or any kind of equipment that is to be operated for a pre-determined period of time for a set fee. For example, in operating a clothes dryer with a set fee of five cents for five minutes, all twelve abutment plates would be advanced on the control member 95. If it were desired to operate the dryer for thirty-five minutes, seven nickles would be consecutively injected into the box by means of the slide 26. Each time the lever 32 would be rocked as previously described by the slide abutment 31, the periphery of ratchet wheel 48 will be rotated a total distance equivalent to the length

of seven teeth. When the first coin is injected, the dryer as well as the motor 96 will be energized. Control member 95 will rotate until seven abutment plates have contacted seven teeth on ratchet wheel 72, to rotate the periphery of the wheel a distance equivalent to the length of seven teeth. Thus, the outward axial movement imparted to ratchet wheel 72 by the rotation of the periphery of ratchet wheel 48 a distance equivalent to the length of seven teeth is compensated for by the inward axial movement imparted by the same amount of rotation of ratchet wheel 72. The dryer and motor 96 will then be de-energized by switch 93 in the manner previously described.

When the abutment plates are arranged to impart rotary movement to ratchet wheel 72 at fifteen minute intervals, as illustrated in FIG. 4, four appropriate coins would be required for one hour of operation. Four coins would move ratchet wheel 48 a distance equivalent to the length of four teeth. As every third abutment plate 98 would contact ratchet wheel 72, one complete revolution of control member 95 would be required to move ratchet wheel 72 a distance equivalent to the length of four teeth to shut off the motor 96 and dryer in the manner just described.

It may be desirable to provide a time control mechanism in which the amount of rotation of ratchet wheel 48 can be readily changed from a peripheral rotation equivalent to the length of one tooth to a peripheral rotation equivalent to the length of two teeth, for each coin injected. The modification illustrated in FIGS. 11 and 12 provides an adjustable lock plate 110 and an adjustable stop member 111. Lock plate 110 is provided with two holes 112 and 113, while the base plate 37 is provided with three holes 114, 115 and 116.

In FIG. 11, screw 117 is threaded through hole 113 of lock plate 110 into base plate 37 to confine the lock plate in the position shown while screw 118 is threaded through hole 115 in base plate 37 into stop member 111. Detent 119 lies in hole 114 and cooperates with screw 118 to rigidly confine the stop member 111 in the position illustrated. When the actuating lever 32 is rocked in the manner previously described, pawl 45 disengages lock plate 110 and is moved in a counter-clockwise direction over ratchet tooth 120 to a position in engagement with lug 56 similar to the position illustrated in FIG. 7. The return stroke of lever 32 will carry pawl 45 into contact with tooth 120 and move tooth 120 to the position occupied by tooth 121 in FIG. 11 before the pawl is locked in place by the plate 110, and lever 32 contacts stop member 111. The ratchet wheel 48 is therefore rotated in a clockwise direction a distance equal to the length of one tooth.

In FIG. 12, the lock plate 110 is moved upwardly from the position illustrated in FIG. 11, by threading screw 117 through hole 112 into the base plate 37. Stop member 111 is moved to the position illustrated in FIG. 12, by threading screw 118 through hole 116 into stop member 111 with detent 119 lying in hole 115. Counterclockwise rotation of lever 32 carries pawl 45 out of engagement with lock plate 110 and ratchet tooth 122. Pawl 45 passes over teeth 123 and 124 to its position on lug 56. The return stroke of lever 32 will carry pawl 45 into contact with tooth 124 and move it to the position occupied by tooth 122. The ratchet wheel 48 is therefore rotated in a clockwise direction a distance equal to the length of two teeth.

By providing the adjustments to regulate the amount of rotation of ratchet wheel 48 by the injection of each coin, as just described, the time control mechanism is even more flexible in providing any desired time cycle. Various settings of abutment plates 98 in connection with the two settings of ratchet wheel 48 provide this great flexibility.

What is claimed is:

1. A timer comprising an axially shiftable externally

threaded stud member, first rotatable means for imparting non-rotational endwise axial movement to said member in one direction, and second rotatable means for imparting rotational and endwise axial movement to said member in the opposite direction, and means on said stud member to actuate an electric contactor.

2. A timer including an electric switch having an actuator element shiftable between circuit closing and circuit breaking positions, a member axially shiftable toward and away from said actuator element, first rotatable means for imparting endwise movement to said member away from said actuator element for shifting said element to a circuit closing position, and second rotatable means fixed to said axially shiftable member coaxially with said first rotatable means for imparting endwise axial movement to said member toward said actuator element, to engage and shift said element to a circuit breaking position.

3. A timer including circuit control means, an axially shiftable member, first means having unidirectional rotation only, for imparting endwise linear movement to said member in one direction only for actuating said circuit control means to a circuit closing condition, second means operable in the same direction of rotation as the first means for imparting a reverse linear endwise movement to said member, and motor means operable incident to completion of a circuit through said circuit control means for driving said second means to impart the aforesaid reverse linear endwise movement to said member for actuating said circuit control means to a circuit breaking condition.

4. A timer including an axially shiftable member, first rotatable means for imparting endwise linear movement to said member in one direction, manually operable means for imparting a step-by-step rotary motion to said first means in said one direction, second rotatable means rotative in the same direction of rotation as said first means, for imparting endwise movement to said member in an opposite linear direction, automatically operable means for imparting rotary motion to said second rotatable means, and means actuated by said member for controlling the operating periods of said automatically operable means.

5. In a device of the class described, the combination of a support member having a bore therein, an internally threaded bushing rotatably mounted in said bore and fixed against endwise axial movement therewith, an externally threaded shaft engaging said internally threaded bushing, a member secured to, carried by and projecting axially from an end of said shaft, means for rotating said bushing, means for precluding rotation of said shaft incident to rotation of said bushing, whereby rotation of said bushing will impart endwise axial movement to said shaft relative to said bushing, and means for rotating said shaft relative to said bushing for imparting a counter axial movement to said shaft.

55 6. A timer including circuit control means, an axially shiftable member for actuating said circuit control means to circuit closing or circuit breaking conditions, first rotatable means for imparting endwise movement to said control member in one direction, and second rotatable means for imparting endwise movement to said control member in an opposite direction.

7. A timer including circuit control means, a member for actuating said circuit control means to a circuit closing or circuit breaking condition, first means mounted for rotation about but fixed against endwise movement along an axis, second means rotatable about and shiftable endwise along said axis, said member being secured to, carried by and projecting from said last mentioned means, means operatively interconnecting said first and second means whereby rotation of said first means will impart axial movement only to said second means, and wherein rotation of said second means will impart axial movement thereof relative to and without rotating said first means.

8. A timer including circuit means, an axially shiftable control member for actuating said means to circuit

closing and circuit breaking conditions, a support member having a bore therein, an internally threaded bushing rotatably mounted in said bore and fixed against endwise axial movement therewith, an externally threaded shaft engaging said internally threaded bushing, said member secured to, carried by and projecting axially from an end of said shaft, means for rotating said bushing, means for precluding rotation of said shaft incident to rotation of said bushing, whereby rotation of said bushing will impart endwise axial movement to said shaft relative to said bushing, means for rotating said shaft relative to said bushing for imparting axial movement to said shaft in an opposite direction, an electric motor, means driven by said motor in driving relationship with said shaft, said circuit control means adapted to close an electrical circuit to said motor incident to axial movement of said member in one direction for imparting rotation to said shaft to move said member in the opposite direction to a circuit breaking position.

9. A timer including circuit control means having an element movable between one or the other of two normal positions to establish a circuit closing or a circuit breaking condition within said means, a member for actuating said element, first means mounted for rotation about but fixed against endwise movement along an axis, second means secured to and carried by said first means, said second means rotatable about and shiftable endwise along said axis and relative to said first means, said member being secured to, carried by and projecting from said last mentioned means, means operatively interconnecting said first and second means whereby rotation of said first means will impart axial movement only to said second means for moving said member away from said circuit control element, and wherein rotation of said second means in the same direction will impart axial movement thereof relative to and without rotating said first means for moving said member toward said circuit control element.

10. A timer including circuit control means having an element movable between one or the other of two normal positions to establish a circuit closing or a circuit breaking condition within said means, an axially shiftable member for actuating said element, an internally threaded bushing, means mounting said bushing for rotation about but fixed against endwise movement relative to an axis, an externally threaded shaft engaging said internally threaded bushing, said member secured to, carried by and projecting axially from an end of said shaft for movement toward and away from said circuit control element, means for rotating said bushing in one direction, means for precluding rotation of said shaft incident to rotation of said bushing whereby rotation of said bushing will impart endwise axial movement to said shaft relative to said bushing, other means for rotating said shaft in the same direction relative to said bushing, means for precluding rotation of said bushing incident to rotation of said shaft whereby rotation of said shaft will impart axial movement thereto in an opposite direction, an electric motor, means driven by said motor in driving relationship with said shaft, said circuit control means adapted to close an electrical circuit to said motor incident to axial movement of said member away from said circuit control element for imparting rotation to said shaft to move said member toward and to engagement with said circuit control member to break the electrical circuit to said motor.

11. A timer including circuit control means having an element movable between one or the other of two normal positions to establish a circuit closing or a circuit breaking condition within said means, a member for actuating said element, first means including a ratchet wheel mounted for rotation about but fixed against endwise movement along an axis, second means including a ratchet wheel secured to and carried by said first

5 means, said second means rotatable about and shiftable endwise along said axis and relative to said first means, said member being secured to, carried by and projecting from said last mentioned means, means operatively interconnecting said first and second means whereby rotation of said first means will impart axial movement only to said second means for moving said member away from said circuit control element, and wherein rotation of said second means in the same direction will impart axial movement thereof relative to and without rotating said first means for moving said member toward said circuit control element, ratchet means operable for imparting a step-by-step rotary motion to the ratchet wheel associated with said first means, drive means engageable with the teeth of the ratchet wheel associated with said second means for imparting rotary motion thereto, an electric motor in driving relationship with said drive means, and means connecting said motor to said circuit control means whereby said motor will be driven during those periods of time when said circuit control element is in a circuit closing condition.

12. A timer including circuit control means having an element movable between one or the other of two normal positions to establish a circuit closing or a circuit breaking condition within said means, an axially shiftable member for actuating said element, an internally threaded bushing, means mounting said bushing for rotation about but fixed against endwise movement relative to an axis, a first ratchet wheel secured to and carried by said bushing, an externally threaded shaft engaging said internally threaded bore, a second ratchet wheel secured to and carried by one end of said shaft, said member secured to, carried by and projecting axially from the other end of said shaft, ratchet means for rotating said bushing in one direction for imparting axial movement to said shaft to move said member away from said circuit control element, means for precluding rotation of said shaft incident to rotation of said bushing whereby rotation of said bushing will impart endwise axial movement to said shaft relative to said bushing, drive means engageable with the teeth of said second ratchet wheel for rotating said shaft in the same direction relative to said bushing, means for precluding rotation of said bushing incident to rotation of said shaft whereby rotation of said shaft will impart axial movement thereto in an opposite direction, an electric motor, said drive means in driven relationship with said motor, said circuit control means adapted to automatically close an electrical circuit to said motor incident to axial movement of said member away from said circuit control element for imparting rotation to said shaft to move said member toward and to engagement with said circuit control member to break the electrical circuit to said motor.

13. An axially shiftable member, including in combination, first rotatable means for imparting endwise axial movement to a second rotatable means to which said member is secured, manually operable means for imparting a step-by-step rotary motion to said first means for imparting endwise movement of said second means in a direction away from said first means, and means for imparting rotary motion to said second rotatable means relative to said first means for returning said second means back to its initial position.

14. An axially shiftable member, including in combination, first rotatable means including a ratchet wheel mounted for rotation about but fixed against endwise movement along an axis, second rotatable means secured to and carried by said first means, means interconnecting said first and second means whereby relative rotation therebetween imparts endwise movement of said second means relative to said first means, said member secured to and carried by said second means, manually operable means for imparting a step-by-step rotary motion to the ratchet wheel of said first means, and means precluding overriding rotation of said ratchet wheel beyond the

step-by-step rotation thereof by said manually operable means.
